(57) **CLAIM**

The ornamental design for a device for synthesizing bio-ink, as shown and described.

DESCRIPTION

FIG. 1 is a perspective view of a device for synthesizing bio-ink, showing our new design;

FIG. 2 is a front elevation view thereof;

FIG. 3 is a rear elevation view thereof;

FIG. 4 is a side elevation view thereof;

FIG. 5 is an opposite side elevation view thereof; and, FIG. 6 is a top plan view thereof.

The broken lines depict portions of the device for synthesizing bio-ink that form no part of the claimed design.
